Primary Examiner — Darlington Ly(74) *Attorney, Agent, or Firm* — McAndrews Held & Malloy, Ltd.(57) **CLAIM**

The ornamental design for a display screen or portion thereof with graphical user interface, as shown and described.

DESCRIPTION

The FIGURE is a front view of a display screen or portion thereof with graphical user interface showing our new design.

The long-dashed broken line showing the display screen or portion thereof and short-dashed broken line showing elements of the graphical user interface do not form part of the claimed design.

1 Claim, 1 Drawing Sheet(56)
